UNITED STATES PATENT OFFICE.

ANTON HUHN, OF MINNEAPOLIS, MINNESOTA, ASSIGNOR TO A. HUHN MANUFACTURING COMPANY, OF MINNEAPOLIS, MINNESOTA, A CORPORATION.

DRIER FOR VARIOUS FORMS OF MATERIAL.

Application filed July 16, 1919. Serial No. 311,201. Renewed June 9, 1924.

To all whom it may concern:

Be it known that I, ANTON HUHN, a citizen of the United States, residing at Minneapolis, in the county of Hennepin and State of Minnesota, have invented certain new and useful Improvements in Driers for Various Forms of Material, of which the following is a specification.

My invention relates to driers for various forms of material and particularly material which might have a tendency to cling to heated surfaces and become scorched or damaged thereby. An object of my invention is to construct a drier which shall use in the largest measure the heat units applied to the drier without injury to the product and which shall effect drying of the product with great discharge and high efficiency. Among the special objects of my invention are the provision of an efficient arrangement of heating pipes and supporting means therefor, the provision of convenient means for supporting the frame of the drier and the provision of means for feeding the material to and through the drier in a uniform stream.

The full objects of my invention will appear in connection with the detailed description thereof and the novel features embodied in my inventive idea will be particularly pointed out in the claims.

In the drawings, illustrating the application of my invention in one form—

Fig. 1 is a central longitudinal section of my drier. Fig. 2 is a section on the line 2—2 of Fig. 1 drawn upon an enlarged scale. Fig. 3 is a section on the line 3—3 of Fig. 1 drawn upon an enlarged scale. Fig. 4 is a section on the line 4—4 of Fig. 5 drawn upon an enlarged scale. Fig. 5 is a detail view mostly in side elevation of a pipe-supporting device. Fig. 6 is a section on the line 6—6 of Fig. 5. Fig. 7 is an enlarged sectional detail view of a cylinder-supporting device. Fig. 8 is a side elevational sectional view of the portion of the drier for feeding in material. Fig. 9 is a view in section on the line 9—9 of Fig. 8. Fig. 10 is a general view in side elevation showing the arrangement for operating different parts of the machine from the same source of power.

The device embodies a frame consisting of a front annular casting 10 and a rear annular casting 11 secured together by

longitudinal members 12, 13, 14 and 15, preferably formed as I-beams secured to the front and rear castings in any suitable manner, as by angle irons 16. The front and rear of the frame are provided with flanges 17 and 18, respectively, underneath which are placed flat blocks 19 and 20 resting upon supporting I-beams 21 and 22 which may be supported on piers or which may rest upon the floor. The adjacent surfaces of said flanges and blocks are provided with curved recesses for receiving cylindrical rods or bearings 23 having headed ends so that the flanges rest upon these cylindrical bearings instead of resting directly upon the blocks. On account of this arrangement the frame may be readily mounted in proper position upon the I-beams and is then secured thereto by bolts 24 passing through the flanges and the horizontal portions of the I-beams. The rear blocks 20 are thicker than the front blocks 19 to cause the machine to slope downwardly from rear to front and, obviously, the slope can be varied by changing the thickness of the blocks at one end. 80

The use of the bearings 23 allows the slope of the frame to be readily changed, since the frame may rock upon the bearings. An outer cylinder 25 is rotatably supported upon rollers 26 at its front and rollers 27 at its rear, these rollers being journaled upon the frame. A pinion 28 meshes with an annular spur gear 29 secured around the front end of said cylinder. The pinion is secured to a shaft 30 to which is also secured a pulley 31 adapted to be driven by a belt 32 from any suitable source of power. The interior wall of the cylinder 25 has secured thereto a plurality of flights 33, while a smaller cylinder 34 is concentrically secured to the outer cylinder and within the same by brace rods 35. The exterior of the cylinder 34 is provided with a plurality of flights 36 which cooperate with the flights 33 to lift the material which is being dried as it is fed into the annular space between the cylinders by suitable means 37 which is preferably of the screw-conveyor type and will be described later. The device for feeding in material is preferably located at the side and above the longitudinal axis of the cylinders, and in order that it may be positioned at either side as desired, openings through the rear casting are provided to both sides and the one not in use is closed 110

22

by a plate 38, as shown in Fig 2. The outer cylinder has its front end rotatable within an annular flange 39 secured to the front casting, and this cylinder has its rear end 5 rotatable within an annular flange 40 secured to the rear casting. The front portion of the machine as shown is made in two parts, consisting of the annular casting 10 and a central casting 9, the two castings being 10 secured together in suitable manner as by passing bolts through their overlapping edges. The casting 9 is hollow and is divided by partitions into a plurality of compartments designated by the numerals 41 to 15 48. A heating medium such as liquid oil is admitted to the compartment 41 through a pipe 49 leading from a suitable retort or heating device not shown. A multiplicity of pipes located within the smaller cylinder 20 34 when this inner cylinder is employed lead from the various compartments to the rear of the machine, where they are bent upon a curve and extended back to the front portion to other compartments as follows. Four 25 pipes 50 leading from the compartment 41 are curved at the rear of the machine so as to extend forwardly and discharge into the compartment 42. Four pipes 51 leading from the compartment 42 are curved at the 30 rear so as to extend forwardly and discharge into the compartment 43. Four pipes 52 leading from the compartment 43 are curved at the rear so as to extend forwardly and discharge into the compartment 44. Four 35 pipes 53 leading from the compartment 44 are curved at the rear so as to extend forwardly and discharge into the compartment 45. Four pipes 54 leading from the compartment 45 are curved at the rear so as to 40 extend forwardly and discharge into the compartment 46. Four pipes 55 leading from the compartment 46 are curved at the rear so as to extend forwardly and discharge into the compartment 47. Four pipes 56 45 leading from the compartment 47 are curved at the rear so as to extend forwardly and discharge into the compartment 48. From the compartment 48 a return pipe 57 leads back to the retort or other device for heating 50 the oil. In Fig. 4 in order to avoid confusion the manner in which each group of pipes leads from one compartment and back to another is indicated for only one of the pipes by dotted lines. All of the 55 pipes 50 to 56 have their front open ends supported by the inner wall of the hollow casting 9. The four pipes 50 are supported at their rear curved portions as follows: An angle bar 58 is bolted to a casting 59 which 60 in turn is bolted to the annular casting 11 so as to lie within the inner circle thereof. Saddle members 60 and 61 which may be cast are hollowed out at spaced intervals so as to partly embrace the pipes 50 on opposite 65 sides thereof, and these members are held together upon the pipes and are attached to the angle bar 58 by bolts which have a reduced portion 62 passing through the saddle members. Nuts 63 on the bolts hold the saddle members 61 against the shoulders 70 of enlarged portions 64 of the bolts. At the ends of the enlarged portions are nuts 65, and these enlarged portions are sufficiently long so that they may slide in the angle bar to compensate for expansion and contraction. 75 In order to obtain greater strength a steel plate 68 may be placed on the outer side of the saddle member 60 for engagement by the nuts 63. The pipes 50 have secured thereon collars 66 which rest upon the saddles, the latter being provided with inclined bosses 67 for this purpose, since the curved portions of the pipes lie slightly out of a vertical plane, due to the fact that the inlet ends of the pipes are not directly above the outlet 80 ends, as will be apparent from Fig. 4. The pipes 51 to 56 are supported by plates 69 through which they pass, these plates in turn being supported by the pipes 50 which pass therethrough. Air is drawn into the drier 85 through an opening 70 at the rear and passes over the pipes 50 to 56, being deflected alternately upwardly and downwardly by the plates 69 which are arranged in staggered relation. The heated air passes out of the 90 forward end of the inner cylinder and into the annular space between the cylinders so that it passes back through the material which is being repeatedly lifted by the flights. The current of air through the apparatus is produced by a fan connected with 95 a casing 71. The manner in which the rear end of the inner cylinder 34 is rotatably supported is best shown in Fig. 7. The casting 59 has bolted to it an annular flange 100 72, the opposite faces of which are engaged by a recessed flange member 73 bolted to the end of the rotatable cylinder so that a tight joint is produced. The mechanism for feeding 105 material into the annular drying chamber 110 is shown particularly in Figs. 8 and 9. The material passes down a chute 74 provided with an observation slide 75 and is delivered in controllable quantity to a casing 76, the lower portion of which contains 115 the screw-conveyor 37 previously referred to leading to the annular drying chamber. In order that the screw-conveyor may deliver a uniform stream which may be regulated as desired, the casing 76 is provided with a 120 feed wheel 77 having a series of blades 78, while a slide 79 is held in adjusted position by a thumb screw 80 so that the space between the feed wheel and the end of the slide may be decreased or increased at will. 125 Graduations 91 may be placed on the slide to indicate the amount of opening thereof. Pulleys 92 and 93 secured respectively to the shafts of the feed wheel and the screw-conveyor serve to drive the same, and these 130

5 pulleys may be driven from the same source of power that drives the cylinders of the drier so that they will be driven and stopped in unison therewith, thereby insuring a 10 uniform flow of material through the drier and out of the discharge chute 94 located at the front thereof.

10 The advantages of my improved drier will be readily understood from the detailed 15 description thereof. Any degree of heat which is desired may be obtained and yet the material operated upon will not be scorched or impaired or even discolored. When an inner cylinder is used the heating 20 pipes are located entirely within the same and the direct radiation of heat from the pipes is transmitted to the walls of said inner cylinder, which in turn transmit the heat to the annular chamber which constitutes the drying area. For this reason there 25 is no loss of heat and the air admitted through the inlet opening becomes rapidly and uniformly heated. This air passes first through the discharge stream of material 30 within the heated chamber leading to the discharge chute or passageway 94. The air at that time is the hottest and driest and therefore removes from the discharging material the last desired amounts of moisture. This air is constrained to pass 35 through the annular drying chamber in a uniform heated stream and is at all times in contact with the double streams of falling material, that is the material falling from the flights in the outer drum upon the inner 40 drum at the upper part of the annular drying chamber, and material falling from the flights on the inner drum to the outer drum in the lower portion of the annular drying 45 chamber. There will also be more or less falling of material at the sides, so that substantially the entire annular chamber will be filled with falling material subjected to the draft of heated air. It thus follows that 50 for the actual space within the drum a maximum amount of drying is effected. By the use of my circulating system in which heated oil is used the air to which the material to be treated is subjected may be 55 highly heated and the temperature thereof may be raised as high as six hundred degrees Fahrenheit. As shown in Fig. 10, a shaft 95 journaled in hangers 96 and 97 is provided at its front end with a clutch 60 pulley 98 driven by a belt 99 from any suitable source of power. The pulley 98 may be clutched and unclutched with relation to the shaft 95 by a hand lever 100. A pulley 101 secured to the shaft 95 is connected to the pulley 31 by the belt 32 whereby the 65 cylinder or drum 33 is rotated. Secured to the shaft 95 toward its other end is a pulley 102 which is connected to the pulley 93 of the screw-conveyor by a belt 103, the size of the pulleys preferably being such that the

screw-conveyor is driven at the same rate of speed as the cylinder 33. Secured to the shaft 95 near the pulley 102 is a pulley 104 which is connected by a belt 105 to the pulley 92 of the feed wheel, the relative 70 size of the latter pulleys being such that the feed wheel is driven at a reduced rate of speed and slower than the screw-conveyor. It will be readily understood that by operating the hand lever 100 that the cylinder, 75 the screw-conveyor and the feed wheel will all stop and start in unison, thereby preventing clogging of the material in the machine.

I claim:

1. A drier comprising a rotatable drum, 80 means for feeding material to be treated into said drum, a plurality of pipes associated with said drum for heating air by oil to substantially 600° F., and means for causing said heated air to pass through said drum. 85

2. A drier comprising a rotatable member, means for causing heated air to pass through said member, a screw-conveyor for feeding material to be treated into said member, and a feed wheel for supplying a 90 uniform stream of said material to said screw-conveyor.

3. A drier comprising a rotatable member, means for causing heated air to pass through said member, a screw-conveyor for feeding material to be treated into said member, a feed wheel for supplying a uniform stream of said material to said screw-conveyor, and means for regulating the quantity of material supplied by said feed 100 wheel.

4. A drier comprising a rotatable member, means for causing heated air to pass through said member, a screw-conveyor for feeding material to be treated into said 105 member, a feed wheel having blades for supplying a uniform stream of said material to said screw-conveyor, and an adjustable slide adapted to be moved toward and away from the downwardly-moving side of said feed 110 wheel.

5. A drier comprising a rotatable member, means for causing heated air to pass through said member, a screw-conveyor for feeding material to be treated into said 115 member, a feed wheel for supplying a uniform stream of said material to said screw-conveyor, and means for driving said rotatable member, said feed wheel and said screw-conveyor from a common source of 120 power.

6. A drier comprising a rotatable drum, a hollow member at one end of said drum, a plurality of compartments in said hollow member, a plurality of pipes connecting said compartments in series, said pipes extending from said hollow member to the other end of said drum and returning to said hollow member, means for causing a heating medium to circulate through said pipes, and 125 130

means for feeding material to be treated into said drum.

7. A drier comprising a frame, a drum rotatably mounted in said frame, a hollow member attached to said frame at one end of said drum, a plurality of compartments in said hollow member, an inlet pipe for a heating medium leading to the first of said compartments, a return pipe for said heating medium leading from the last of said compartments, a plurality of pipes connecting said compartments in series, said pipes extending from said hollow member to the other end of said drum and returning to said hollow drum, and means for feeding material to be treated into said drum.
8. A drier comprising a frame, a drum rotatably mounted in said frame, a hollow member attached to said frame at one end of said drum, a plurality of compartments in said hollow member, a plurality of sets of pipes connecting said compartments in series, said pipes extending from said hollow member to the other end of said drum and returning to said hollow drum, means for supporting one of said sets of pipes from the frame at the end opposite said hollow

member, means for supporting the other sets of pipes from said first-mentioned set of pipes, means for causing a heating medium to circulate through all of said pipes, and means for feeding material to be treated into said drum.

9. A drier comprising a frame, blocks for supporting the ends of said frame, cylindrical bearings interposed between said frame and said blocks, a drum rotatably mounted in said frame, and means for feeding material to be treated into the said drum.

10. A drier comprising a frame, flanges on the bottom of said frame at the ends thereof, blocks for supporting the ends of said frame, transverse grooves in the adjacent faces of said flanges and blocks, cylindrical bearings in said grooves whereby said frame is pivotally mounted, a drum rotatably mounted in said frame, and means for feeding material to be treated into said drum.

In testimony whereof I hereunto affix my signature.

ANTON HUHN.
